CLAIM

The ornamental design for a motor vehicle rear lower bumper, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front perspective view of a motor vehicle rear lower bumper showing our new design;

FIG. 2 is a rear view thereof;

FIG. 3 is a front view thereof;

FIG. 4 is a side view thereof;

FIG. 5 is top view thereof; and,

FIG. 6 is a bottom view thereof.

1 Claim, 5 Drawing Sheets

(5 of 5 Drawing Sheet(s) Filed in Color)
